UNITED STATES PATENT OFFICE

EMIL A. BAUMBACH, OF CHICAGO, ILLINOIS

METHOD OF PACKING DIE SETS

Application filed June 1, 1931. Serial No. 541,341.

My invention relates to the art of packing, and more particularly to the packing of a die set for shipment.

In the shipment of die sets, it has heretofore been the practice to insert a block of wood between the proximal surfaces of the punch holder and the die shoe. This method, however, has been found unsatisfactory for the reason that in many instances the 10 leader pins have been bent by rough handling or dropping, due to the fact that the wooden block would act as a fulcrum about which the punch holder might move.

An object of my invention is to provide a 15 method of packing die sets for shipment wherein the danger of bending leader pins is reduced to a minimum.

A further object is to provide a method of 20 packing which may be practiced with great economy.

Other objects will be apparent from the specification and drawing.

Figure 1 is a perspective view of a die set 25 incorporating my invention;

Fig. 2 is a section on the line 2—2 of Fig. 1, and

Fig. 3 is a perspective view of my packing element.

Referring to the drawing in detail, the embodiment shown comprises a die shoe 1 being provided with leader pins 2 over which the punch holder 3 may be placed by means of the holes 4 provided for this purpose. Between the adjacent surfaces of the punch holder and die shoe is placed one or more of the packing elements 5, which, as indicated in Figs. 1 and 3, normally positions the die shoe 1 and punch holder 3, the said packing element 30 comprising a relatively short tube of paper, wood pulp or some other cellulose material having yielding or compressible qualities together with a slight degree of resiliency. This tube may be in cross section, of any desired 35 or convenient shape, but is preferably circular.

While I have shown in the drawing the packing element as having its axis at right angles to the surfaces of the die shoe and punch holder, it will be evident that the axis

might intersect the surfaces of the die shoe at other angles and still be effective.

By exhaustive tests and experiments and in actual practical use, the invention thus shown and described has proved to be an important improvement in the art of packing die sets, and has greatly reduced injury to the leader pins of die sets. If a set, packed as described, is roughly handled or dropped, the tubular packing elements 5 will yield somewhat, as they are of compressible, crushable material so that the shock of impact is lessened by the cushioning effect thus obtained. The tool holder may mash the packing member somewhat and slide a short distance toward the die shoe, the leader pins 2 entering farther into the leader pin holes 4, but there is not the danger of bending the leader pins that existed with the method of packing where substantially rigid incom- 60 pressible spacer blocks were used.

Further modifications will be apparent to those skilled in the art and it is desired, therefore, that my invention be limited only by the prior art and the scope of the appended 65 claims.

Having thus described my invention, what I claim and desire to secure by Letters Patent is:

1. The method of packing a die set for 80 shipment comprising placing the tool holder in position with respect to the die shoe with the leader pins of the die shoe engaging the openings in the tool holder and placing between the proximal surfaces of the die shoe 85 and the tool holder a tubular spacer member of compressible material having sufficient rigidity to normally position the tool holder with respect to the die shoe with the axis of the tubular member extending transversely 90 with respect to said proximal surfaces.

2. The method of packing a die set for 95 shipment comprising placing the tool holder in position with respect to the die shoe with the leader pins of the die shoe engaging the openings in the tool holder and placing between the proximal surfaces of the die shoe and the tool holder a tubular spacer member of crushable material having sufficient rigidity to normally position the tool holder with 100

respect to the die shoe with the axis of the tubular member extending transversely with respect to said proximal surfaces.

3. The method of packing a die set for shipment comprising placing the tool holder in position with respect to the die shoe with the leader pins of the die shoe engaging the openings in the tool holder and placing between the proximal surfaces of the die shoe and the tool holder a tubular spacer member of cellulose material having sufficient rigidity to normally position the tool holder with respect to the die shoe with the axis of the tubular member extending transversely with respect to said proximal surfaces.

In witness whereof, I have hereunto subscribed my name.

EMIL A. BAUMBACH.
